UNITED STATES PATENT OFFICE

101,724

DESIGN FOR A SIRUP DISPENSING CONTAINER OR SIMILAR ARTICLE

Everett Worthington, Chicago, Ill.

Application July 10, 1936, Serial No. 63,767

Term of patent 14 years

To all whom it may concern:

Be it known that I, Everett Worthington, a citizen of the United States and resident of Chicago, Cook County, Illinois, have invented a new, original, and ornamental Design for a Sirup Dispensing Container or Similar Article, of which the following is a specification, reference being had to the accompanying drawing, forming part thereof.

Fig. 1 is a front view in perspective of the article, showing my design, and

Fig. 2 is a partial side view, also in perspective thereof.

I claim:

The ornamental design for a sirup dispensing container or similar article as shown.

EVERETT WORTHINGTON.
